Primary Examiner—Ted Shooman*Assistant Examiner*—C Tuttle*(74) Attorney, Agent, or Firm*—Ian F. Burns**CLAIM**

The ornamental design for a wagering device display, as shown and described.

DESCRIPTION

FIG. 1 is a perspective view of the wagering device display; FIG. 2 is a front elevational view of the wagering device display.

FIG. 3 is a top plan view of the wagering device display; and,

FIG. 4 is a right side elevational view of the wagering device display, the left side being a mirror image thereof.

“The broken line showing the structure surrounding the design and the elements in the interior of the design is for illustrative purposes only and forms no part of the claimed design”.
